UNITED STATES PATENT OFFICE.

OSCAR H. BROWN, OF SALEM, MASSACHUSETTS, ASSIGNOR TO THE TURNER TANNING MACHINERY COMPANY, OF PEABODY, MASSACHUSETTS, A CORPORATION OF MAINE.

WORK SUPPORT FOR LEATHER-WORKING MACHINES.

Application filed August 26, 1922. Serial No. 584,450.

This invention relates to a work support or table for hide and leather working machines of the character shown and described in U. S. Patent No. 784,017, dated February 5 28, 1905.

The work support or table of the machine shown in the patent referred to, is provided with a bolster of felt, leather or other yielding material, upon which the 10 hide, skin or leather is placed, and which is movable or shiftable with relation to the table, a portion of the bolster lying against one side of the table being connected with the portion lying against the opposite side 15 of the table by chains which engage sprocket wheels on a shaft supported at the top of the table and over which the bolster is passed.

The present invention has for its object to 20 provide a superior table or work support having a shiftable bolster; whereby in the operation of the machine undue strain upon the bolster and the work thereon is avoided, and whereby the use of the chains and 25 sprocket wheels is dispensed with, thereby avoiding annoying delays in the operation of the machine due to breaking of said chains by undue strain placed upon them by the working tools or members acting on 30 the work supported by the bolster.

The invention further has for its object to provide for adjusting the bolster with relation to the table to take up the stretch in the bolster which may be caused by the working 35 tools in the operation of the machine, and thereby provide for obtaining and maintaining any desired tension on the bolster.

These and other features of this invention 40 will be pointed out in the claims at the end of this specification.

Fig. 1 is a front elevation with parts broken away, of a work support or table embodying this invention:

Fig. 2, a side elevation of the table shown 45 in Fig. 1;

Fig. 3, a cross section on the line 3—3, Fig. 1;

Fig. 4, a detail in elevation to show the 50 adjusting mechanism for the bolster;

Fig. 5, a side elevation of Fig. 4 looking toward the left; and

Fig. 6, a detail in side elevation looking 55 toward the left of Fig. 5.

Referring to the drawing, *a* represents the table proper which may be of any suitable or usual construction, and which is herein represented as composed of matched boards:

The table *a* is substantially flat and is provided at its top with a rounded upper edge, 60 which may be formed by a round wooden rod *b* fitted into a substantially circular groove in the top of the table *a*.

The table *a* is provided with a bolster *c* of felt, rubber, leather or other suitable 65 cushioning material, and said bolster is laid over the top of the table *a* and covers the opposite sides of the latter more or less, and is designed to support the hide, skin or leather which is to be treated with the operating tools or working members of the machine, which latter may be the same as that shown in the patent referred to, except as to the table or work support.

The portions of the bolster *c*, which lie 70 against the opposite sides of the table *a* may for convenience be termed members and are numbered 10, 12, and provision is made for positively or mechanically moving one of 75 said members when the table is moved with relation to the other of said members so as to shift the bolster on the table.

In the present instance, one construction or arrangement is shown for effecting this 80 result. To this end, the member 10 at its 85 opposite sides and near its lower end has fastened to it, rack bars 13 provided with a plurality of slots 14 which form teeth 15 in said bars. Each rack bar 13 is fastened to the bolster *c* by a clamping bar 16 and 90 bolts 17.

The rack bar 13 is movable in a guideway formed by a bar 18 secured to the table *a* and a grooved bar 19 secured to the bar 18 and having a portion thereof separated from 95 the bar 18 to form the guideway in which the rack bar 13 slides.

The rack bar 13 is provided at its outer side with a flange or lip 20 which extends 100 into the groove 21 in the bar 19 and serves 105 to prevent lateral displacement of the bolster on the table.

The member 12 of the bolster, which is located on the opposite side of the table *a* has fastened to it at its opposite sides and 110 near its lower end like rack bars 22. Each

rack bar 22 is provided with slots 23 forming teeth 24, and is clamped to the member 12 by a bar 25 and bolts 26. Each rack bar 22 is movable in a guideway formed by a bar 27 secured to the table *a* and by a bar 28 secured to the bar 27 by the bolts 29. The bar 28 is provided with a portion which is separated from the bar 27 by a space which forms the guideway in which the rack bar 22 slides, and is also provided with a longitudinally extended groove 129 for the reception of the flange or lip 30 on the rack bar 22.

Each pair of rack bars 13, 22, has cooperating with it a toothed wheel or pinion 31, whose teeth are designed to engage the teeth of said rack bars, and as a result, the toothed wheel is rotated by one of said rack bars, and acts as a driver to effect movement of the other of said rack bars.

The rack bar 13 is provided with a lug or projection 32 and the rack bar 22 is provided with a lug or projection 33, which co-operate with suitable stops or devices on the machine to prevent movement with the table of said rack bars and the ends of the bolster to which they are attached in the same manner as described in the patent referred to.

In the machine shown in the patent referred to, the bolster member 12 is dragged over the top of the table in one direction by the bolster member 10, when the projection 32 attached to the latter engages the stop, not shown, which cooperates with it, and the bolster member 10 is dragged over the top of the table in the opposite direction when the projection 33 attached to the bolster member 12 engages its cooperating stop, as described in the said patent.

In the present instance, this dragging action is avoided, and both bolster members are positively moved in opposite directions, because the rack bars 13, 22 attached to them are positively moved, and as a result the bolster is shifted over the top of the table in opposite directions with a minimum effort and without undue strain being placed upon it.

In operation with the table herein shown, the lug 32 attached to the bolster member 10 is brought into engagement with its co-operating stop on the upward movement of the table *a* and after the latter has passed between a lower pair or set of working members, the same as described in the patent referred to.

On the continued upward movement of the table *a*, the bolster member 10 is prevented from moving with the table, by the engagement of the lug 32 with its co-operating stop, while the other bolster member 12 is positively moved in the same direction as the table, which is effected by the toothed wheel 31, which moves with the table, being caused to rotate by the now stationary rack

bar 13, and in turn causing the rack bar 22 and the bolster member 12 to be positively moved upward in the same direction as the table, thereby effecting a shifting of the bolster over the top of the table and accomplishing this shifting of the bolster without strain being imposed upon the bolster.

After the bolster has been shifted on the table, the lug 32 is released from its stop, and the bolster is then carried by the table between the second pair of working members, and after this takes place, the lug 33 on the bolster member 12 engages its stop and prevents the bolster member 12 from moving with the table, so that on the further upward movement of the table, the toothed wheel 31 is caused to be rotated by the now stationary rack bar 22, and acts as a driver for the rack bar 13, which is positively moved or pushed upwardly on the continued upward travel of the table, thereby effecting a shifting of the bolster over the top of the table in the opposite direction.

At or about the time the bolster has been shifted so as to restore the members 10, 12 to their normal positions with relation to the table, the lug 33 is released from its stop.

Provision is made for adjusting the tension on the bolster. To this end, the toothed wheel 31 is mounted on a shaft 40 which is supported in a sliding block 41 movable lengthwise between the plates or bars 18, 27 by an adjusting screw 42 extended through a bottom bar 43 and provided with a collar 44 and having an angular end position 45 for engagement with a wrench. By turning the adjusting screw 42 in one direction, the block 41 is moved downward, and the tension on the bolster is increased, as both members 10, 12 are simultaneously moved downward, due to the fact that they are connected with the sliding block 41 through the rack bars 13, 22, toothed wheel 31 and shaft 40.

By turning the adjusting screw in the opposite direction, the sliding block 41, the shaft 40, the toothed wheel 31 and the rack bars 13, 22 are moved upwardly as well as the bolster members 10, 12, thereby relieving the tension upon the bolster.

The shaft 40 is guided in its movement by guide pieces 47, 48 located between and secured to the bars 18, 27, and provided with slots 49 through which the ends of the shaft 40 are extended. The shaft 40 is provided at its outer end with a collar 50, and the slots 49 may and preferably will be provided at their upper ends with an enlargement 51.

It will be observed that the toothed wheel 31 is driven by one rack bar and acts as a driver for the other rack bar, when the bolster is shifted on the table, and when the tension of the bolster is adjusted, the toothed wheel acts as a connector or coupler for the rack bars, so that they may be moved simul-

taneously in the same direction. From the above description, it will be observed that the bolster is shifted with a downward pull on one bolster member and with a positive

- 5 upward push on the other, for when the lug 32 engages its co-operating stop and the table continues upward, the stop prevents upward movement of the bolster member 10 with the table and the effect is the same as 10 a down pull upon the bolster member 10, and at the same time, the bolster member 12 is positively pushed upwardly by the toothed wheel 31 which moves upwardly the rack bar 22 attached to the bolster member 12.

15 One embodiment of the invention is herein shown, but it is not desired to limit the invention to the particular construction shown.

Claims:

- 20 1. A work support for hide and leather working machines comprising a table, a bolster extended over the top of the said table and having members cooperating with the opposite sides thereof to support the 25 work, rack bars attached to said bolster members, and a toothed wheel carried by said table and engaging said rack bars to positively move one of said rack bars and its bolster member in the same direction as 30 said table when the latter is moved lengthwise of the other of said rack bars.

35 2. A work support for hide and leather working machines comprising a table, a bolster extended over the top of the said table and having members cooperating with the opposite sides thereof to support the work, rack bars attached to said bolster members, a toothed wheel engaging said rack bars, a shaft for said wheel, a sliding carrier for 40 said shaft movable with said table, and means for moving said sliding carrier to effect simultaneous movement of said rack bars and said bolster members.

45 3. A work support for hide and leather working machines comprising a table, a bolster extended over the top of the said table and having members cooperating with the opposite sides thereof to support the work, and means located between said bolster mem-

bers and cooperating therewith for positively moving one of said bolster members in the same direction as the table is moved and toward the other of said bolster members when the latter is prevented from moving with the table.

50 4. A work support for hide and leather working machines comprising a table, a bolster extended over the top of the said table and having members cooperating with the opposite sides thereof to support the work, 55 means located between said bolster members and cooperating therewith to connect them together, and means for moving said connecting means and said bolster members to simultaneously move the latter in the same direction with relation to the table.

5. A work support for hide and leather working machines comprising a table, a bolster extended over the top of the said table and having members cooperating with the 60 opposite sides thereof to support the work, and means cooperating with said bolster members and movable with said table for pushing upwardly the lower portion of one of said bolster members when said table is 65 moved upwardly with relation to the other of said bolster members to shift the portion of the bolster normally lying over the top of the table onto the side of the table whose bolster member is not moving with the table.

70 6. A work support for hide and leather working machines comprising a table, a bolster extended over the top of the said table and having members cooperating with the opposite sides thereof to support the work, 75 and means carried by said table and rendered effective by movement of the latter with relation to one of said bolster members to positively push the other of said bolster members in the same direction as the table is moved 80 and thereby shift the bolster with a downward pull on one bolster member, and with a positive upward push on the other bolster member.

85 In testimony whereof, I have signed my name to this specification.

OSCAR H. BROWN.
